UNITED STATES PATENT OFFICE

2,511,514

POWDERED MATERIAL SPREADER

Clifford L. Rosselot, Owensville, Ohio

Application February 1, 1946, Serial No. 644,928

9 Claims. (Cl. 275—2)

1

My invention relates to spreaders for powdered limestone, and other minerals and powdered or granular land treating substances. The improvements incident to the present invention have application to the same problems as dealt with in my U. S. Letters Patent No. 2,369,755, dated February 20, 1945.

In the said Letters Patent, the distributor for the powdered material was a single unit, of such great length as to require removal from the vehicle containing the supply, in order for the vehicle to pass through a gate. Accordingly it was made detachable as a unit and was arranged to be coupled up very simply to the driving means for the same.

It is an object of the present invention to provide means whereby the distributor which is alike in its general respects to that of my former patent, can be lifted away in two sections, the act of lifting away and removal requiring simply the release of a pair of hanger clips, and the replacement into driving relation being simply a reversal of the removal steps. As an advantage of this modification the driving elements for the distributor can be fixtures on the supply vehicle and no part of the drive be lifted away for passage of the device as a whole through a normal farm gate.

In the device of my former patent difficulty was encountered in obtaining a uniform spread of material. An object of the present invention is to provide in a very simple way for a substantial equivalent discharge of material all along the two laterally extended tubes constituting the distributor.

The above objectives and other improvements over the former structure are provided for according to my present invention of which I have illustrated a preferred embodiment, it being understood that the structures shown are but an example illustrating the invention involved which will be set forth in the appended claims.

In the drawings:

Figure 1 is a plan view of the chassis of a motor vehicle and a powdered material supply, delivery and distributing elements mounted thereon.

Figure 2 is a detail side elevation of the distributor when in place.

Figure 3 is a section on the line 3—3 of Figure 1.

Figure 4 is a section on the line 4—4 of Figure 3.

Figure 5 is a bottom plan view of the distributor showing the damper strip.

2

Figure 6 is a section on the line 6—6 of Figure 4, and

Figure 7 is a section on the line 7—7 of Figure 4.

5 Figure 8 is a detail plan view of the clamp as taken along the plane of line 8—8 of Figure 2. The chassis of a motor vehicle is indicated at 1 and on it is located a V-shaped cross section body 2, for containing mineral or other powdered material to be distributed over the land. A power take off 3 from the drive motor for the vehicle is connected to one of two worm shafts 5 and 6. The worm shafts lie along side of each other in the bottom of the V-shaped body, which contains two channels one for each worm shaft. The drive to worm shaft 5 is transmitted to worm shaft 6 by means of a pair of gears 7, and 8, so that the worm 6 turns in opposite directions to worm 5. For this reason the worms have the thread thereon of opposite hand. It is my experience that a double worm feed along the bottom of the V-shaped body is more effective than a single worm feed, and that to have the two worms of opposite hand as to thread and driving them in opposite directions tends to prevent bridging and gives a more uniform and positive feed than the single worm of my former structure.

20 The two worms each have their end bearings in boxes 9 and 10, at the rear end of the V-shaped body, which boxes have spouts 11 and 12 projecting downwardly from their interior, into which the two worms feed a supply of mineral from the bottom of the V-shaped body. In my former construction, the delivery from a single worm was divided into two parts as it fell from the delivery spout at the end of the single worm. This did not result in as uniformly accurate a delivery of two equal streams of material as does the structure just now described.

25 The spindle of one of the worms, in this instance the spindle 5a of the driven worm shaft 5 extends through a suitable antifriction bearing in the box 9, and is equipped with a pulley wheel 13. By means of this wheel, the worms in the delivery tubes are to be driven.

30 The drive is provided for as follows: Bolted on flanges 14 on a plate 15 secured below the two boxes for the end worm bearings, are a pair of mounting plates 16. These plates have mounted therein roller bearings 17, 18, for a hollow spindle 18. This spindle has a grooved pulley 19 thereon lying between the two plates, 35 and a belt 20 which is twisted as indicated and

passes around the pulley 13 on the worm shaft and around this pulley 19.

The internal bore of the spindle 18 is squared, and there are a series of fixed pins 21 projecting outwardly from the two plates 16. In order to position the plates 16 so that there is proper tension on the belt the flanges 14 will be slotted where the bolts 16a for the two plates pass through them. It will be noted that one of the spouts, the spout 11, must be diverted somewhat to clear the driving pulley arrangement.

The delivery devices are in the form of tubes 22 and 23. These tubes in a form of the machine constructed by me are each over nine feet long and they have a series of slots 24 along the bottom thereof for discharge of material. The slots in this particular machine are around three inches apart on centers. It seems best to slant them somewhat instead of making these slots at right angles to the axis of the tubes. The slots may be, for example, two inches long. Within each tube is a feed worm 25 which has a roller bearing 26 at its outer end. The spindles 27 of these worms may be in the form of a piece of tubing with the helical feeding rib secured thereto by welding. Into the inner ends of each tubular spindle a driving pin 28 is forced, with a tight fit. The pins have squared ends which fit slidably into the squared interior of the spindle 18. Each tube has a face plate welded thereto at its inner end as shown at 29 which plate has holes in it to engage over the pins 21 that project from the two plates which bear the said spindle 18.

Thus when a tube with its worm in place and assembled as shown is ready to be set into place (as shown with relation to the end of the right hand tube 22 in Fig. 4), the squared driving pin is thrust into the end of the spindle 18 at which time the pins on the mounting plate will enter the holes in the tube end plate. The parts will then be in the position shown as to the tube 23 in Figure 4, and the drive will be connected and the tube held at its inner end against falling and also against rotation.

There are hangers 30 at each side of the chassis of the vehicle. I have shown only one such hanger on each side of the chassis but it is to be understood that a plurality of such could be had if desired. The hangers 30 are curved so as to receive the tubes 22 and 23 and support them intermediate their ends. Secured to each hanger 30 is a hook 30a. Clamps 31 to hold the tubes in the hangers 30 are so arranged as to retain them against endwise play also.

Such clamps 31 (see Figures 2, 8, 9 and 10) are constructed as follows: Hinged to the tip of each hanger 30 at pivot 31b is a yoke 31a and pivoted on the arms of the yoke 31a at pivot 31b are the arms of a bail or lever 31c having a closed end 31d; pivoted to the bail 31c at pivot 31e is the yoke 31f having a cross bar 31g.

Each of the tubes 22 and 23 has lugs 32 on their upper side.

In operation the clamps 31 are manipulated as follows: As shown in Figure 9 the yoke 31f is first brought down towards the lug 32 and its cross bar 31g dropped into the hook 30a. In this position (Figure 9) the clamp 31 is in a relaxed position and not yet in compression, both pivot points 31b and 31e being above the center line between pivot 31b and the center point of cross bar 31g. The operator then pushes (with his hand or by proper use of the lever or bail

31c) the pivot points 31b and 31e below the aforementioned center line. To do this requires that the hanger 30 be sprung outward slightly. When the points 31b and 31e are both below said center line, however, the clamp 31 (see Figure 10) is again in a relaxed position but the yoke 31f now rests on the tube 23 about its lug 32. When the lever or bail 31c is next pushed toward the yoke 31f about the pivot 31e, the pivot 31b is brought above said aforementioned center line and the hanger 30 is again sprung. When the lever or bail 31c nears the yoke 31f, the hanger 30 being sprung will cause the clamp mechanism to be in compression and the lever or bail 31c will snap down towards the yoke 31f until the closed end 31d contacts the end of the hook 30a. This is the position of the clamp 31 when in use (i. e. under compression) as seen in Figure 2. In this position the pivot point 31b is above said aforementioned center line, while the pivot 31e is below it and the hanger 30 is slightly sprung thus causing the mechanism of clamp 31 to be in compression.

If a heavy shock is imparted to the clamp 31 through the tube 23 the yoke 31f will be pushed up and the pivot 31e raised to that position shown in Figure 9. The clamp 31 now being relaxed the cross bar 31g may be easily lifted from the hook 30a.

It should be noted that, with a little practice, the operator, when applying the clamp, may put the various yokes and bail directly in the position illustrated in Figure 10 without first positioning the clamp as at Figure 9. This will avoid having to spring the hanger 30 just to get from the position of Figure 9 to that of Figure 10 as first above described. In this connection it should be noted that both Figures 9 and 10 show the clamp mechanism in a relaxed position and that Figure 2 shows said clamp in actual locking position under compression.

When it is desired to pass the device through a gate, the levers or bails 31c of the clamps 31 are raised and the cross bar 31g lifted from the hook 30a, and the two tubes then individually lifted and pulled out endwise. Each tube has a shallow hopper 33 at its inner end which when the tube is mounted comes underneath the open end of one of the spouts 11 and 12.

It remains to describe and explain the feed control device. In connection with my original machines the discharge holes in the tubular distributor were simple round holes which could be opened or closed by a sliding damper or dampers. There was no way of controlling the amount of opening for each individual hole. It is indeed thought impractical to have a series of individual dampers or slides one for each hole, because there are some seventy or more holes in the two tubes.

In my present device I provide for controlled openings in the discharge holes or slots with reference to each other. The reason why this is required is that with some materials the amount which discharges from the holes nearest the drive end of the distributing tube worms, i. e., nearest the hoppers on the tubes, is considerably greater than the amount which discharges from the outer holes. In other materials the holes can be left open in full, and fairly equal amounts will fall through each hole. Where there is a difference in amount which discharges it grades away gradually from the receiving end to the outer end of each tube.

With the arrangement now described in which

each tubular distributor element presents a series of adjacent slots in a line along the bottom thereof. I provide a control plate or damper in the form of a long thin piece of sheet metal 34 as wide as the slots, one for each of the tubes. I also provide a set of clamping rings 35, preferably three in number, which engage around the tube and clamp the damper strip in place. The damper strips 34 are slightly curved in cross section to fit flat against the two tubes.

Now since the damper strip is flexible it can be pulled out of line. As indicated in Figure 5, the strip on each of the two tubes 22 and 23 has been clamped at its inner end so as to close all but a small amount of the first discharge slot. It then slopes slightly spirally with reference to the tube so as to leave open increasing amounts of each discharge slot until at the outer end the slots are almost entirely exposed. The three clamping rings hold the strip in adjusted position. Also the inner end of each damper strip may be held in a strap on the bottom of the tube as indicated at 35a, this suspension leaving freedom for damper adjustment.

It is not necessary to enforce a position of the damper strips in an even spiral. They can be almost straight with the row of slots from the first ring to the second ring and then slope spirally more sharply.

In operation the vehicle is brought to a position for operation. Since the driving wheels for the vehicle are not connected with the drive for the mineral delivery and discharge, the delivery and discharge mechanism can be driven for a short period with the slots fully exposed by the damper or closing strips. Small piles of mineral will collect on the ground and the operator can gauge the relative amounts in the piles. He then loosens the clamps, and arranges the damper strip at each side to the required spiral to shut off the holes delivering the most and leave open those holes which fell behind in the operation. This has been found to be a simple operation and assures that a job of placing mineral on the soil, say for example lime, will be uniform, and when some other material, such as phosphates, which behave in a different way is being spread, again a uniform job entirely across the space subtended by the distributor device can be obtained.

It will be evident that within the novelty inherent in the structure described, various mechanical changes can be made which will be equivalents in structure and behavior and I wish to cover these in the appended claims. Thus the damper strips could be inside the tube and held in place by means of studs projecting through the slots.

Having thus described my invention, what I claim as new and desire to secure by Letters Patent is:

1. In combination with a vehicle, a powder distributing member located transversely of the vehicle and extending beyond the sides thereof, said distributing member comprising two equal sections adapted to be secured together for common operation when in operative position on said vehicle, each of said sections comprising a casing having efflux openings therein, a worm feed in each said casing, a hopper for each said casing, and means for quickly detachably mounting the two said casings on the vehicle, and a quickly detachable drive from the vehicle to the worm feeds, said mounting means comprising brackets on the vehicle in which the casings rest,

and latch means to hold the casings against jarring out of the brackets.

2. The combination with a vehicle having a V-shaped body for containing pulverulent material to be delivered to the land, a pair of worms in the apex of said body, adapted to deliver each a stream of equal amount from the back end of said V-shaped body, a driving mechanism and a distributor operated thereby at the rear of said V-shaped body, said distributor comprising a pair of laterally extending tubes having hopper means in position when the tubes are mounted to receive material each from one of said streams, means for removably supporting said tubes on the rear of the vehicle, worms in said tubes having ends to fit slidably into driving relation with the driving mechanism, a series of slots lengthwise of the tubes for delivery of material, and means for closing the slots in selective amounts along the tubes so that the slots near the inner end of said tubes are more nearly closed than the slots near the outer end of said tubes, whereby equal amounts may be delivered from the arrangement entirely along the said tubes, but each tube may be lifted away for passage of the vehicle through a gateway, said slot closing means comprising a strip which abuts the surface of a said tube adjacent the slots provided therein, said strip being provided with means for securing it to said tube in a predetermined twisted position for the purpose described.

3. In a powdered material distributor for the land, the combination with means for supplying streams of powdered material to a long tubular distributor having a series of discharge openings therein in a row lengthwise thereof, a flexible damper strip shaped to fit said tubular distributor and capable of being twisted so as to cover said row of holes at least partially and in varying degrees, from a minimum degree of opening at the material receiving portion of said distributor towards a maximum degree of opening at the other end of said distributor, and means for retaining said strip in desired position of distortion spirally of the tubular distributor, for the purpose described.

4. The combination of claim 3 in which the means for retaining the said strip are a series of clamps engaging the strip and the tubular distributor.

5. In a powdered material distributing machine having means for delivering a stream of powdered material, a tube projecting laterally from the machine, a worm in the tube driven to feed material along the tube, said tube having means to receive the material at one end thereof, a series of holes lengthwise of the tube in a straight line constituting discharge openings, and a strip arranged to abut the surface of the tube adjacent said openings to serve as a damper therefor, said strip passing across a series of said holes, and means for adjusting said strip in different positions at a slant to said straight line, thereby disclosing different amounts of the said openings, said different amounts ranging from a minimum degree of opening at the material receiving end of said tube towards a maximum degree of opening at the outer end of said tube.

6. The combination of claim 5 in which the openings are in the form of slots transverse the tube.

7. The combination of claim 5 in which the said strip extends the full length of the tube.

8. In a spreading machine for distribution of 75 pulverulent material onto the soil, a transverse

tube and screw conveyor element of such length as to require lifting away from the machine for passage through a gate or doorway, means on the machine for driving the screw element, said screw and said means having slidable connection, and means on the machine for supporting the tube intermediate its length comprising a hanger, and a clamp secured thereto, said clamp comprising a pair of elements pivoted to a third element, one of said pair of elements having a hook engagement with an inner portion of the hanger, the other of said pair of elements having pivotal engagement with an outer portion of the hanger, said third element being arranged to alternately extend and contract the lengthwise extent of the pair of elements combined.

9. In a spreading machine for distribution of pulverulent material onto the soil, a transverse tube and screw conveyor element of such length as to require lifting away from the machine for passage through a gate or doorway, means on the machine for driving the screw element, said screw and said means having slidable connection, and means on the machine for supporting the tube intermediate its length, said means comprising a hanger, and a clamp thereon, said clamp comprising a pair of yokes pivoted to a bail, each at a different point on said bail, one of said yokes

being also pivoted to the hanger and the other having projecting means to seat in a hook on the opposite side of the hanger, said bail being pivoted to the two yoke members so as to deflect the pivotal points of said members on said bail and thereby extend said pair of yokes in length to effect a clamping of the tube, one of said pair of yoke elements having an opening therein to fit about a lug on said tube.
